UNITED STATES PATENT OFFICE.

JOHN P. WEIS, OF NYACK, NEW YORK, ASSIGNOR TO METROPOLITAN SEWING MACHINE CORPORATION, A CORPORATION OF DELAWARE.

SEWING-MACHINE.

1,328,108.

Specification of Letters Patent.

Patented Jan. 13, 1920.

Application filed July 20, 1918. Serial No. 245,823.

To all whom it may concern:

Be it known that I, JOHN P. WEIS, a citizen of the United States, residing at Nyack, in the county of Rockland and State of New York, have invented certain new and useful Improvements in Sewing-Machines, of which the following is a specification.

This invention relates to sewing machines and comprises an improved mechanism for laying a cross thread on top of the work and which cross thread is stitched down by a pair of needles for the purpose of making covered seams or joining pieces of goods, the object of the invention being to provide an improved mechanism for laying the top cross thread in the path of the needles to be stitched down by the needle threads and to be of such a design as to not interfere with the hands of the operator in the handling 20 of the work and in general to be out of the way.

One of the advantages of the present improvement is that the mechanism is simple, consisting of a few parts arranged so as to give a rotary motion to the thread carrying finger around the needles. The motion of the finger being so arranged as to not interfere in any way with the conducting of the needle threads to the needles. That is to say 30 the finger oscillates in a circular path around the needles with the needle bar as the center, the finger being shaped spirally so that the movement of the main portion of the finger carrier will oscillate from one side 35 around in back to the other side around in front of the needle bar and the needles in such a way so as not to interfere or strike the needle threads or obstruct the line of vision for threading the needles. In nearly 40 all machines of this character is it necessary to turn the machine to some given position to get the thread carrier out of the way of the needles for the purpose of threading. Such is not the case with the present improvement on account of the main movement thereof being entirely in the rear of the needles, whereas in former constructions 45 the thread carriers passed in front of the needles so as to contact with the needle 50 threads.

Another advantage resides in the manner in which the thread carrier is mounted on the bushing in the lower needle bar bearing so as to have a rise and fall movement identical with that of the presser foot and to ob-

tain such rise and fall movement by means of the rack and pinion gear connection with the vertically oscillating shaft carried in the head of the machine, which in turn is connected with the presser foot mechanism for 60 rise and fall movement.

Another advantage is in the arrangement of the top finger thread guide, which may be adjustably secured to the presser foot shank having a universal adjustment, as well as another form shown, carried by the frame of the machine and capable of vertical rise and fall movement, because of its connection with the presser foot mechanism.

Another advantage resides in the fact that 70 the connections for operating the top thread carrying finger are located near the top of the machine frame leaving a clear place underneath the arm thereof for free manipulation of the work.

In the drawings accompanying and forming a part of this specification, Figure 1 is a front end view of so much of a sewing machine as is necessary to illustrate the improvements; Fig. 2 is a perspective view of 80 the thread carrying finger, thread guide, presser foot and needle mechanism. This view also shows a portion of work which has been stitched; Fig. 3 is a detail view showing the manner in which the finger co-acts 85 with the thread guide and the needles in the formation of the stitch; Fig. 4 a view similar to Fig. 3, showing another position of the finger with relation to the needles in the formation of the stitch; Fig. 5 is another detail view showing the relation of the thread carrying finger, thread guide and needles in the formation of the stitch; Fig. 6 is a detail top plan view showing a portion of the presser foot, thread guide, thread finger and 90 the needles in the formation of the stitch. In this view the finger has reached near the extreme of its movement to the left in rear of the needles and shows how the left hand needle steps into the loop carried by the 100 thread finger; Fig. 7 is a fragmentary detail of the needle thread take-up, showing the looper and the needles co-operating therewith; Fig. 8 is a view similar to Fig. 7 showing the take-up in another position so as to 105 draw up the outside needle loop immediately as it is cast from the point of the looper so as to make a tight stitch; and Fig. 9 is a perspective view illustrating a different manner of attaching the thread guide.

Similar characters of reference indicate corresponding parts in the several figures of the drawings.

In the drawings the bed plate 1 of the machine, and the cloth plate 2 thereof form a part of the machine frame of the well-known Metropolitan construction having the usual hand wheel and needle lever 3, bearing on the stud 4 so as to give reciprocating movement to the needle bar 5, which operates in the bearings 6 and 7. The top of the needle bar carries a thread eyelet 8 for conducting the needle threads. The bottom end of the needle bar carries a needle chuck 9 having a pair of needles 10 coöperating with the usual thread carrying looper 11 which is carried by the usual operating mechanism generally indicated by 12, and which is operated into and out of the needle loops and also from the front to rear of the needles, in the usual manner, so as to make the regular 2-needle 3-thread ornamental stitch on the bottom of the work.

The main or bottom shaft 13 of the machine is mounted in the usual bearings and the machine is equipped with the ordinary feed mechanism generally indicated by 14. The main shaft near the rear bearing carries a gear 15 in mesh with a gear 16. This last gear is mounted on a shaft 17 which is parallel with the main shaft and carried by the rear of the frame. A crank ball stud 18 is secured to the gear 16 and to a part 19, which has a rod 20 connected therewith, the other end of which carries a part 21 operating on a ball 22 secured to one end 23 of the bell crank lever 24. This lever 24 oscillates on the rear end 25 of the needle lever stud 4, and this stud is provided with a lock nut 40 and an anti-friction collar 26. The arm 27 of the bell crank lever 24 carries a ball stud and part 28 having connected therewith the rod 29. The other end of this rod carries a ball part 30 which is secured to the lever 31. This lever 31 is provided with a hub 32 operating between the bearings 32^a of a yoke 32^b, which yoke is connected with the presser bar at 32^c for movement therewith, and this lever 31 is secured to the rock shaft 33, which rocks in the bearings 34 and 35 of the machine frame.

Secured to this vertical rock shaft 33 below the bearing 35 is a hub 36 of the segmental gear 37 which has teeth along its curved face 38, and provided with top and bottom plates 39. The teeth 38 are in mesh with the teeth of a pinion 40. The top and bottom plates overlap the top and bottom walls of the pinion teeth so as to control the vertical rise and fall movement of the whole. The pinion gear is integral with the sleeve 41 which surrounds the needle bar 5 and operates in the bearing 6 in a rotary oscillating manner. This sleeve 41 projects from the bottom of the bearing 6 sufficiently to

have clamped thereon a split collar 42 which is secured by a clamp screw 43, passing through the split portion 44. This collar terminates in a downward projection portion 45, slotted as at 46 and having a threaded end so as to receive a nut 47, which forms a clamping means for holding the thread carrying finger 48. This finger is bent in a spiral shape so as to partly project around the needles. The bottom end thereof is notched as at 49 in a suitable manner to pick up and carry the thread around the needles in the formation of the stitches.

Coöperating with the thread carrying finger is a thread guide 50, which conducts the ornamental cross thread 51 in the path of the thread carrying finger (see Fig. 2). This thread guide is located at one side of the needles, which are arranged in a plane at right angles to the line of feed, and slightly in the rear of said needles, so that in the operation of the thread carrying finger said finger moves in a circular path from a point in the rear of the needles around in front of the needles sufficiently to carry a loop of the cross thread 51 into such position that the needle farthest removed from the thread guide can enter such loop.

While I have shown the thread guide located adjacent to the right hand needle the machine from which the drawings were made may be operated when so adjusted so as to have these conditions reversed. That is to say, the thread guide may be located adjacent the left hand needle and by reversing the timing of the movements of the thread carrying finger the operations thereof will be in reverse direction, and when so arranged will produce substantially the same stitch formation as when the parts are arranged as shown.

I have shown two forms of mounting the thread guide, one secured to the presser foot shank and the other to the machine frame.

The presser foot mechanism comprises a presser bar 52, which operates in the bearings and is under spring tension as usual and has secured at the bottom end thereof the presser foot shank 53 (see Figs. 1 and 2). This shank has attached to its rear wall an angle bracket 54, carrying holes 55 tapped therein for the purpose of attaching thereto the shank 56 of the thread guide 50, which may be slotted as at 57 to permit suitable adjustment up and down and in and out. The other form of thread guide (see Fig. 9) is arranged so as to be carried by the hub 58 of the machine frame. A gib 59 is secured to the front wall of the hub and has one of its edges beveled, and a slot is milled into the hub vertically and parallel with the needle bar so as to form a dovetail groove 60 to receive a dovetail slide 61. This slide carries an attached plate 62 provided with a forked end 63 so as to co-act with the pin 130

portion 64 carried by the presser bar, so as to give vertical rise and fall movement to the thread guide.

While I have shown two forms of thread guides each having a vertical movement with the presser foot mechanism, I do not wish to be limited to such construction as with the mechanism shown the needles rise sufficiently above the presser foot and the thread handling end 49 of the thread carrying finger 48 also operates sufficiently above the presser foot to perform their functions while the presser foot is co-acting with the feed in its rise and fall movements to feed the work 15 in a proper manner even when it is crossing seams.

In most machines for doing this character of work it is necessary to have a thread carrying finger almost rub the top surface 20 of the presser foot and in that instance it is essential to have a finger and thread guide rise and fall with the foot so as not to damage the same when crossing seams or when removing or inserting the work. The 25 presser foot shank 53 has an enlarged portion 65 provided with slots to receive the vertical outside portions 66 of the foot 67. These sections are spring depressed by springs 68 secured to the presser foot shank 30 and having their opposite ends resting on pins 69 to give downward pressure to the outside sections 67. The middle section 70 of the foot is integral with the portion 65 of the foot and has the usual needle opening 71 35 for the pair of needles and which has a short tongue over which the stitches are formed. Fig. 2 shows the manner in which the work 72 is fed into the machine and guided by the lip 73 of the guide plate 74. 40 The other part of the work is in this instance a tubular strip 75 such as is used for finishing the tops of ladies' vests around the neck and arm hole openings, or lace or embroidery may be stitched in place of a tubular strip.

The stitch is represented at 76, Fig. 2, it being understood that the bottom covering stitch is of the well known twin needle three-thread variety. The tubular strip passes 50 underneath the overhanging portion 77 of the guide plate 74. This guide plate is mounted on a swing bracket 78 attached to the slide plate 79 by a shoulder screw 80.

The class of work this type of machine is 55 used for often requires the needles to be set close to one another, usually one-eighth of an inch, so as to produce a narrow seam. There has always been difficulty in controlling the formation of the stitches when the 60 needle gage is narrow because the left hand needle being set lower than the other, the tendency is for it to deflect a larger loop and as the looper is entering the needle loops the left hand loop frequently twists so as to 65 cross over the loop formed by the other nee-

dle. The result is an imperfect stitch formation. Then again it is more difficult to draw up a tight stitch on the left hand needle than it is on the right and to overcome these difficulties, I have provided a 70 simple take-up. This comprises a bracket 81 attached to the top bearing 7 of the machine frame and it is adjustable in two directions. The bracket has a vertical extension 82, having an inclined edge 83 and an inclined edge 75 84. The former co-acts with the eyelet 8 so as to draw the needle thread 85 to the position shown in Fig. 8 indicated by 86 because this thread extends from one wall 87 of the eyelet 8 to the other wall 88 so as to take up 80 the loop 89 as it slips from the looper 11 in the formation of the stitch, when the needles are descending. The thread co-acting with the inclined edge 84 in the upward movement of the needles drawing the thread out 85 to the position 90 shown in Fig. 7, draws the thread so as to take up the outside needle loop indicated by 91, making the loop just large enough for the looper 11 to enter 90 properly.

The adjustment of the vertical extension 82 which may be termed the take-up is arranged so that the amount of thread taken up by it can be regulated. By changing its vertical position the time at which it takes 95 up the thread may be changed. The operation or handling of the needle threads is as follows:

The two needle threads pass from the ordinary tensions (not shown) to the stationary eyelet 92 and thence to the needle lever eyelet 93 and thence to the eyelets in the wall 87, the left hand thread then passes to the eyelet in the wall 88 and then directly to the eye of the needle, while the right hand 100 needle thread passes from the wall 87 directly to the needle. From the foregoing it will be clear that the take-up 82 merely handles the outside or left hand needle 105 thread.

The cross thread 51 of the thread finger 50 is under the tension control 50^A and this tension is opened by a wire 50^B carried by the presser bar 52 to release the thread when the bar is lifted for removal of the work. 115 An eyelet 50^C attached to the head at 50^D conducts said thread to the guide 50.

It is obvious that the details may be more or less changed without departing from the spirit or scope of the present improvement. 120

I claim as my invention:

1. The combination of a work support, a presser foot, a presser bar carrying said foot, a feeding mechanism, a needle bar, a pair of needles carried by said needle bar and arranged in a plane at right angles to the line of feed, a thread guide disposed at one side of the needles and slightly in the rear of the plane of the needles, a thread hook movable across the line of feed to engage a cross 125 130

thread extending through said thread guide and back across the line of feed for forming a loop in the cross thread, said hook and thread guide being so disposed relatively to the needles as to position the loop in the cross thread for the entrance only of the needle farthest removed from the thread guide, means surrounding the needle bar for supporting said thread hook, and means for operating said supporting means.

2. The combination of a work support, a presser foot, a presser bar carrying said foot, a feeding mechanism, a needle bar, a pair of needles carried by said needle bar and arranged in a plane at right angles to the line of feed, a thread guide disposed at one side of the needles and slightly in the rear of the plane of the needles, a thread hook movable across the line of feed to engage a cross thread extending through said thread guide and back across the line of feed for forming a loop in the cross thread, said hook and thread guide being so disposed relatively to the needles as to position the loop in the cross thread for the entrance only of the needle farthest removed from the thread guide, means surrounding the needle bar for supporting said thread hook, means for operating said supporting means, and take-up means for taking up the thread of one needle to a greater extent than that of the other.

3. In a sewing machine, the combination of stitching mechanism comprising a pair of needles, looper mechanism coöperating with the needles, a cross thread guide, and a single cross thread carrying a finger coöperating with the pair of needles and movable in a circular path practically around the path of the needles, said finger having a spiral formation.

4. In a sewing machine, the combination of stitching mechanism comprising a pair of needles, looper mechanism coöperating with the needles, a presser foot, a cross thread guide movable with the presser foot, and a single cross thread carrying finger coöperating with the pair of needles and movable in a circular path practically around the path of the needles, said finger having a spiral formation.

5. In a sewing machine, the combination of stitching mechanism comprising a plurality of needles, looper mechanism coöperating with the needles, and a single thread carrying finger coöperating with the needles and movable in a circular path practically around the path of the needles and comprising a spirally formed finger.

6. In a sewing machine, the combination of stitching mechanism comprising a needle bar carrying a pair of needles, looper mechanism coöperating with the needles, and a single cross thread pick up finger coöperating with the needles and having its pivotal

axis coincident with the axis of the needle bar and movable in a circular path practically around the path of the needles.

7. In a sewing machine, the combination of stitching mechanism comprising a needle bar carrying a pair of needles, looper mechanism coöperating with the needles, and a single cross thread carrying finger coöperating with the needles and having its pivotal axis coincident with the axis of the needle bar and movable in a circular path practically around the path of the needles, said finger having a spiral formation.

8. In a sewing machine, the combination of stitching mechanism comprising a needle bar carrying a pair of needles, looper mechanism coöperating with the needles, a single cross thread carrying finger coöperating with the needles and having its pivotal axis coincident with the axis of the needle bar and movable in a circular path practically around the path of the needles, said finger having a spiral formation, and a thread guide located to one side and slightly in the rear of the needles.

9. In a sewing machine, the combination of stitching mechanism comprising a needle bar carrying a pair of needles, looper mechanism coöperating with the needles, a single cross thread carrying finger coöperating with the needles and having its pivotal axis coincident with the axis of the needle bar and movable in a circular path practically around the path of the needles, said finger having a spiral formation, presser foot mechanism, and a thread guide carried by said presser foot mechanism.

10. In a sewing machine, the combination of stitching mechanism comprising a needle bar carrying a pair of needles, looper mechanism coöperating with the needles, a single cross thread carrying finger coöperating with the needles and having its pivotal axis coincident with the axis of the needle bar and movable in a circular path practically around the path of the needles, said finger having a spiral formation, presser foot mechanism, and a thread guide carried by said presser foot mechanism and located to one side and slightly in the rear of the needles.

11. In a sewing machine, the combination of stitching mechanism comprising a needle bar carrying a pair of needles, looper mechanism coöperating with the needles, a vertically supported rock shaft, means for rocking said shaft, a rack connected with said rock shaft, and a cross thread pick up finger having a part encircling said needle bar and having a gear coöperating with said rack.

12. In a sewing machine, the combination of stitching mechanism comprising a

needle bar carrying a pair of needles, looper mechanism coöperating with the needles, a vertically supported rock shaft, means for rocking said shaft, a rack connected with said rock shaft, and a cross thread carrying finger having a part encircling said needle bar and having a gear coöperating with said rack, said finger having a spiral formation.

10 13. In a sewing machine, the combination of stitching mechanism comprising a needle bar carrying a pair of needles, looper mechanism coöperating with the needles, a vertically supported rock shaft, means for rocking said shaft, a rack connected with said rock shaft, a cross thread pick up finger having a part encircling said needle bar and having a gear coöperating with said rack, and a thread guide co-
20 operating with said finger.

14. In a sewing machine, the combination of stitching mechanism comprising a needle bar carrying a pair of needles, looper mechanism coöperating with the needles, a vertically supported rock shaft, means for rocking said shaft, a rack connected with said rock shaft, a cross thread carrying finger having a part encircling said needle bar and having a gear coöperating with
25 said rack, and presser foot mechanism, said presser foot mechanism having connection with said rack and gear whereby the cross thread finger is raised and lowered with the presser foot mechanism.

30 15. In a sewing machine, the combination of stitching mechanism comprising a needle bar carrying a pair of needles, looper mechanism coöperating with the needles, a vertically supported rock shaft, means for rock-
35 ing said shaft, a rack connected with said rock shaft, a cross thread carrying finger having a part encircling said needle bar and having a gear coöperating with said rack, and presser foot mechanism, said presser
40 foot mechanism having connection with said rack and gear whereby the cross thread finger is raised and lowered with the presser foot mechanism and a thread guide carried by the presser foot mechanism to one side
45 and slightly to the rear of the needles.

50 16. In a sewing machine, the combination of stitching mechanism comprising a needle bar carrying a pair of needles, looper mechanism coöperating with the needles, a vertically supported rock shaft, means for rocking said shaft, a rack connected with said rock shaft, a cross thread carrying finger having a part encircling said needle bar and having a gear coöperating with said rack,
55 presser foot mechanism, said presser foot mechanism having connection with said rack and gear whereby the cross thread finger is raised and lowered with the presser foot mechanism and a thread guide carried by
60 the presser foot mechanism to one side and
65

slightly to the rear of the needles, and take-up means effective to take up the slack of one needle thread to a greater extent than that of the other whereby both needle stitches will be of uniform formation.

70 17. In a sewing machine, the combination of stitching mechanism comprising a needle bar carrying a pair of needles, looper mechanism coöperating with the needles, a spirally formed cross thread carrying finger coöperating with the needles, and take up means for taking up the thread of one needle to a greater extent than that of the other.

75 18. In a sewing machine, the combination of stitching mechanism comprising a pair of needles, a needle bar carrying said needles, looper mechanism coöperating with the needles, a cross thread guide, a single cross thread carrying finger coöperating with the pair of needles and having its pivotal axis substantially coincident with the axis of the needle bar and movable in a circular path practically around the path of the needles, and take up means effective to take up the slack of one needle thread to a greater extent than that of the other whereby both needle stitches will be of uniform formation.

80 19. In a sewing machine, the combination of stitching mechanism comprising a pair of needles, looper mechanism coöperating with the needles, a cross thread guide, a single cross thread carrying finger coöperating with the pair of needles and movable in a circular path practically around the path of the needles, said finger having a spiral formation, and take up means effective to take up the slack of one needle thread to a greater extent than that of the other whereby both needle stitches will be of uniform formation.

85 100 20. In a sewing machine, the combination of stitching mechanism comprising a pair of needles, a needle bar carrying said needles, looper mechanism coöperating with the needles, a presser foot, a cross thread guide movable with the presser foot, a single cross thread carrying finger coöperating with the pair of needles and having its pivotal axis substantially coincident with the axis of the needle bar and movable in a circular path practically around the path of the needles, and take up means effective to take up the slack of one needle thread to a greater extent than that of the other whereby both needle stitches will be of uniform formation.

90 110 115 21. In a sewing machine, the combination of stitching mechanism comprising a plurality of needles, a needle bar carrying said needles, looper mechanism coöperating with the needles, thread carrying finger mechanism coöperating with the needles and having its pivotal axis substantially coincident with the axis of the needle bar and movable in a circular path practically around the

path of the needles, and take up means effective to take up the slack of one needle thread to a greater extent than that of the other whereby both needle stitches will be of uniform formation.

22. In a sewing machine, the combination of stitching mechanism comprising a needle bar carrying a pair of needles, looper mechanism coöperating with the needles, a cross thread pick-up finger coöperating with the needles and having its pivotal axis coincident with the axis of the needle bar and movable in a circular path practically around the path of the needles, and take up means effective to take up the slack of one needle thread to a greater extent than that of the other whereby both needle stitches will be of uniform formation.

23. The combination of a work support, a presser foot, a presser bar carrying said foot, feeding mechanism, a needle bar, a pair of needles carried thereby and arranged in a plane at right angles to the line of feed, a thread guide disposed at one side of the needles and slightly in the rear of the plane of the needles, a thread hook movable across the line of feed to engage the cross thread extending through said thread guide and back across the line of feed for forming a loop in the cross thread, and means surrounding the needle bar and supporting the thread hook whereby said hook has its pivotal axis coincident with the axis of the needle bar, said hook and thread guide being so disposed relatively to the needles as to position the loop in the cross thread for the entrance only of the needle farthest removed from the thread guide, means connecting said thread hook with the presser foot bar, and take up means for taking up the thread of one needle to a greater extent than that of the other.

24. In a sewing machine, the combination of presser foot mechanism, feeding mechanism, a pair of needles, a thread guide disposed at one side of the needles and slightly in the rear of the plane of the needles, a cross thread carrying finger coöperating with the

needles and having its pivotal axis coincident with the axis of the needle bar and movable in a circular path practically around the path of the needles and effective to pick up a cross thread extending through said thread guide, said thread carrying finger and thread guide being so disposed relatively to the needles as to position the loop in the cross thread for the entrance only of the needle farthest removed from the thread guide, and take up means for taking up the thread of one needle to a greater extent than that of the other.

25. In a sewing machine, the combination of stitching mechanism comprising a needle bar carrying a pair of needles, looper mechanism coöperating with the needles, a single cross thread pick-up finger coöperating with the needles and having its pivotal axis coincident with the axis of the needle bar and movable in a circular path practically around the path of the needles, and a cross thread guide disposed at one side of the needles and slightly to the rear of the plane thereof.

26. The combination of a work support, a presser foot, a presser bar carrying said foot, a feeding mechanism, a needle bar, a pair of needles carried by said needle bar and arranged in a plane at right angles to the line of feed, a thread guide disposed at one side of the needles and slightly in the rear of the plane of the needles, and a thread hook carried independently of the presser bar and movable across the line of feed to engage a cross thread extending through said thread guide and back across the line of feed for forming a loop in the cross thread, said hook and thread guide being so disposed relatively to the needles as to position the loop in the cross thread for the entrance only of the needle farthest removed from the thread guide.

Signed at 1822 Park Row Building, New York city, New York, this 19th day of July, 1918.

JOHN P. WEIS.
